CLAIM

We claim the ornamental design for a tippet holder, as shown and described.

DESCRIPTION

FIG. 1 is a top, right, front perspective view of an aspect of a tippet holder on a pack according to our design; FIG. 2 is a top, left, front perspective view thereof; FIG. 3 is a bottom, right, rear perspective view thereof; FIG. 4 is a front elevation view thereof; FIG. 5 is a rear elevation view thereof; FIG. 6 is a left elevation view thereof; FIG. 7 is a right elevation view thereof; FIG. 8 is a top plan view thereof; and, FIG. 9 is a bottom plan view thereof. The dash-dot broken lines of the figure drawings are included to show unclaimed subject matter only for the purpose of illustrating environment and form no part of the claimed design. The dash-dot broken lines of the figure drawings are included to show the boundaries of the claimed design and form no part of the claimed design.

1 Claim, 5 Drawing Sheets
